UNITED STATES PATENT OFFICE.

KENNETH IRWIN CROSSLEY AND WILFRED LE PLASTRIER WEBB, OF MANCHESTER.
ENGLAND.

INTERNAL-COMBUSTION OIL ENGINE.

1,423,088.

Specification of Letters Patent.

Patented July 18, 1922.

Application filed July 27, 1920. Serial No. 399,396.

(GRANTED UNDER THE PROVISIONS OF THE ACT OF MARCH 3, 1921, 41 STAT. L., 1313.)

To all whom it may concern:

Be it known that we, KENNETH IRWIN CROSSLEY and WILFRED LE PLASTRIER WEBB, both subjects of the King of Great Britain and Ireland, and both residing at Openshaw, Manchester, in the county of Lancaster, England, have invented certain new and useful Improvements in Internal-Combustion Oil Engines (for which we have obtained a patent in Great Britain, No. 104,089, dated May 5th, 1916), of which the following is a specification.

Our invention relates to internal combustion engines of the kind which uses oil as fuel and which works on the four stroke cycle and in which towards the end of compression stroke the oil fuel is injected as spray by itself (without the aid of separate compressed injection air) into the compressed and heated air in the combustion chamber.

The object of our invention is to so improve the construction and arrangement of the combustion chamber as to increase the efficiency of the engine and at the same time to provide in the combustion chamber a disposition of the air admission valve and exhaust valve particularly suitable for an engine of the inverted vertical type.

Our invention consists in constructing the combustion chamber in such manner that the air admission valve and exhaust valve open directly into it, and of such convenient shape that a long, clear, diverging path is provided from the point of spray admission in which the injected oil spray may diffuse and vaporize and mix with the hot compressed air therein, and that in addition the area of wall surface is comparatively small in proportion to the contained volume. A chamber which is substantially oviform (or somewhat flattened oviform when the piston is at the end of its compression stroke) is the best for our purpose, and such shapes are not difficult to obtain with, for instance, low compression pressures or with small valves, but if the compression pressure is fairly high, or the valves large, it is somewhat more convenient, in order to make suitable room for the air admission and exhaust valves, if the shape approximates more to that of an ellipsoid (or flattened ellipsoid when the piston is at

the end of the compression stroke). The oil is sprayed into the chamber from one or both ends and in the case of the oviform chamber preferably from the smaller end. The chamber is arranged with its ends at the sides of the cylinder, the longitudinal axis of the chamber being placed at about right angles to the axis of the engine cylinder, the axes of the chamber and of the cylinder being in or near one plane. The upper and larger portion of the chamber is formed by the cylinder end and is water-jacketed wherever possible. The lower portion is formed by the top end of the piston or a portion thereof. The piston may be waterjacketed or not as preferred. The air admission valve and the exhaust valve are of the mushroom type and are arranged in the upper and water-jacketed part of the chamber and open directly into the chamber, and are placed with their spindles either inclined to each other or parallel with each other. The valve spindles lie in or about a plane either common to or perpendicular to the plane in which lie both the longitudinal axis of the chamber and the axis of the cylinder.

If the heat due to the compression of the air in the cylinder and combustion chamber is sufficient to effect ignition no separate igniter is necessary unless specially desired as an alternative. In the latter case or if the heat due to the compression is not sufficient to effect ignition, an igniter may be fitted at any convenient position in the combustion chamber.

With a combustion chamber of substantially oviform or ellipsoidal shape and arranged as described the oil spray on entering the combustion chamber has a long free path of increasing area in which it may diffuse and vaporize and mix with the compressed and heated air therein. The shape of the chamber presents a comparatively small area of containing wall surface in proportion to its cubic capacity and therefore ensures no excessive loss of heat through the walls due to the water jacket. The effective water-jacketing of this combustion chamber ensures the engine working with a lower mean temperature in the cylinder, prevents overheating troubles, enables water injection to be dispensed with, ensures a greater weight

of contained air, allows the combustion of a greater amount of oil spray and enables the power of the engine to be increased. It also enables higher air compression pressure to be used, and ensures a greater degree of economy in fuel consumption in proportion to the power developed.

The combustion chamber may be fully open to the cylinder at all times or it may be connected to the cylinder by means of a passage of more or less restricted area, such restriction being effected either by the size of an open passage or by a partial closing of a passage by means of a projection on the end of the piston entering it towards the end of the compression strokes. In the latter case the cross sectional area of the passage (when not allowing for the reduction caused by the projection on the piston) may be equal to that of the combustion chamber but is less than the cross sectional area of the cylinder. The passage between the combustion chamber and the cylinder is located at any convenient position on the side of the combustion chamber.

We have described in our British specification No. 2976 of 1915 a combustion chamber of similar type with the air admission valve and the exhaust valve arranged in a manner which is particularly suitable for an engine with a horizontal cylinder, but in our present invention the air admission valve and the exhaust valve are arranged in a manner which is particularly suitable to an engine in which the cylinder is of the vertical inverted type.

We have illustrated our invention by a series of more or less diagrammatic figures in which similar parts are denoted by similar letters. The waterjacketed combustion chamber is shown at A, the piston at B, the cylinder at C, and oil injector at D, the air admission and exhaust valves at E, E, the water jacket at F F. The part marked G may be used as an inspection door or as an igniter or as a starting valve, or either the air admission valve or the exhaust valve may be placed at about this position if desired as shown for example in Figure 10. The water jacket is only shown in detail in Figures 1 and 2 but it is to be understood it would be used in all cases.

Figures 1, 2 and 3 represent respectively sectional elevations and a plan of a combustion chamber and other parts constructed and arranged according to our invention. In this case the chamber is oviform in shape and freely open to the cylinder at all times. The longitudinal axis of the combustion chamber is shown at right angles with the axis of the cylinder. The oil injector is shown at the smaller end of the chamber at the side of the cylinder. The air admission valve and the exhaust valve are shown with their spindles diagonal with each other and

lying in the same plane as that in which lie the longitudinal axis of the chamber and the axis of the cylinder.

Figures 4, 5 and 6 represent a combustion chamber which is of a flattened oviform shape (flattened in the direction of the axis of the cylinder). The valves may be arranged inclined to each other as represented by the dotted lines in Figure 4, or they may be parallel as shown in Figure 7, or they may be arranged as represented in Figure 5 inclined to each other in a plane perpendicular to the common plane in which lie the axes of the combustion chamber and cylinder.

Figures 7, 8 and 9 represent a combustion chamber of a flattened ellipsoidal shape with the air admission valve and exhaust valve spindles arranged parallel to each other. With an ellipsoidal shape of chamber and particularly if flattened somewhat there is more room for the valve E shown on the left hand side in Figures 7 and 9 than there is for the corresponding valve in the oviform shape of the chamber as will be clearly seen by referring to Figures 9, 6 and 3 respectively.

It will readily be understood that if the combustion chamber is of somewhat flattened oviform or flattened ellipsoidal shape when the piston is at the end of the compression stroke, the chamber will more nearly approximate to a substantially oviform or ellipsoidal shape somewhat before the end of the compression stroke at about the period when the oil is being sprayed in, and somewhat after the end of the compression stroke at about the period of maximum combustion temperatures. In Figure 7 to illustrate this we have shown the oil injector on a centre line somewhat below the longitudinal centre line of the flattened oviform chamber and somewhat nearer to what would be the centre line of the chamber when the piston has moved down and the chamber has more nearly approached the ellipsoidal shape.

Figures 10 and 11 represent a combustion chamber which is connected to the cylinder by a passage of restricted area. The passage may be restricted either simply by an open passage such as H, in which case the end of the piston is made as shown by the full lines, or the passage may be restricted by the partial closing of the passage H by means of a projection on the piston such as J (shown in Figures 10^a and 11^a) entering it towards the end of the compression strokes.

Having now described our invention, what we claim as new and desire to secure by Letters Patent is:—

1. In four stroke cycle internal combustion oil engines, the combination comprising a cylinder, an ellipsoidal combustion chamber having its longitudinal axis at right angles to the axis of the said cylinder,

an oil injector at an end of the said chamber, admission and exhaust valves at the upper side of the chamber and a water jacket on the exterior of the cylinder and chamber, as set forth.

2. In four stroke cycle internal combustion oil engines, the combination comprising a cylinder, an ellipsoidal combustion chamber having its longitudinal axis at right angles to the axis of the said cylinder, an oil injector at an end of the said chamber, admission and exhaust valves at the upper side of the chamber inclined to each other in a plane perpendicular to the plane in which lie both the longitudinal axis of the chamber and the axis of the cylinder, and a water jacket on the exterior of the cylinder and chamber, as set forth.

3. In four stroke internal combustion oil engines, the combination comprising a cylinder, an ellipsoidal combustion chamber having its longitudinal axis at right angles to the axis of the said cylinder, a piston in said cylinder forming when at the inner end of

its stroke the lower side of the said chamber, 25 an oil injector at an end of said chamber, admission and exhaust valves at the upper side of the chamber and a water jacket on the exterior of the cylinder and chamber, as set forth.

4. In four stroke cycle internal combustion oil engines, the combination comprising a cylinder, an ellipsoidal combustion chamber having its longitudinal axis at right angles to the axis of the said cylinder, a 35 passage between the said cylinder and said chamber, a piston in the cylinder having a projection which enters the said passage when the piston nears the end of its in stroke, an oil injector at an end of said chamber, admission and exhaust valves at the upper side of the chamber and a water jacket on the exterior of the cylinder and chamber, as set forth.

In testimony whereof we have signed our 45 names to this specification.

KENNETH IRWIN CROSSLEY.

WILFRED LE PLASTRIER WEBB.
